LOCOMOTIVE AND STOKER THEREFOR

Edwin Archer Turner, New York, and Charles J. Surdy, Tuckahoe, N. Y., assignors to The Standard Stoker Company, Incorporated, a corporation of Delaware

Application July 27, 1937, Serial No. 155,902

10 Claims. (Cl. 110—103)

This invention relates to locomotives having a firebox which is divided into a pair of furnaces or combustion chambers. More particularly, the present invention relates to stokers arranged for supplying fuel to such furnaces or combustion chambers.

The efficiency of a locomotive boiler depends to a great extent upon the evaporation surface of its firebox since it is obvious that the greater 10 the evaporating surface, less time is required to transform water into steam.

Accordingly, one object of this invention is to increase the evaporating surface of a locomotive boiler firebox.

15 In carrying out this object, and as a still further object of our present invention, the locomotive boiler firebox is divided longitudinally into a pair of furnaces or combustion chambers by means of a hollow, water circulating structure.

20 Another object of this invention resides in the provision of a stoker especially adapted to feed fuel into each of the furnaces or combustion chambers provided in the locomotive boiler firebox.

25 It is also an object of this invention to provide a stoker arranged to feed fuel into each of the furnaces or combustion chambers in a manner to maintain a predetermined pressure of steam in the boiler.

30 A still further object of this invention is to provide a stoker so arranged that one furnace is constantly being supplied with fuel during normal operation of the locomotive while the other furnace receives fuel only at such times whenever peak loads are imposed on the locomotive 35 boiler.

Another object of this invention resides in providing suitable means for maintaining a pilot fire within the furnace into which fuel is delivered by the stoker at intervals necessary to reach peak demands.

Other objects and their advantages will become apparent as the following description is read in connection with the accompanying drawings, in which:

Figure 1 is a longitudinal view of a locomotive, the greater portions of which have been broken away, with the invention in position;

Figure 2 is a plan view of the structure shown in Figure 1 as viewed along the line 2—2 of Figure 3;

Figure 3 is a transverse vertical section taken on the line 3—3 of Figure 1;

Figure 4 is a rear elevation of the locomotive taken on the line 4—4 of Figure 2;

Figure 5 is a sectional view of the control valve shown in Figure 4;

Figure 6 is an enlarged plan view of the stoker drive engine with portions broken away to show certain parts in section;

Figure 7 is an enlarged fragmentary view taken along the line 7—7 of Figure 4;

Figure 8 is a view somewhat similar to Figure 4 showing a modification; and

Fig. 9 is a fragmentary sectional view on the line 9—9 of Fig. 8.

Referring first to Figures 1 and 7, inclusive, L indicates a locomotive, T the tender and C a coupling therebetween. The locomotive L comprises a frame 10 which is carried upon the running gear 11 in known manner. Above the frame 10 is a boiler 12 which includes a firebox 13 and flues 14 for conducting products of combustion from the firebox 13 to the smokebox 15.

Drafting of the firebox 13 is accomplished by 20 means of a nozzle 16 disposed within the smokebox 15 and through which nozzle steam from the locomotive driving cylinders (not shown) is exhausted to atmosphere from the stack 17. The swiftly moving exhaust steam within the smokebox 15 creates a sub-atmospheric condition within the firebox 13 and causes air to be admitted thereto through suitable openings in and between grates 18.

The firebox 13 is defined by the grates 18, the 30 back flue sheet 19, the back wall 20, side walls 21, 22, and the crown sheet 23. In accordance with the present invention, the firebox 13 is divided longitudinally into a primary furnace 13a and an auxiliary furnace 13b by means of a 35 low water circulating wall 24 attached at its upper side to the crown sheet 23 and thence extending downwardly to fit loosely into a recess 25 formed with the center grate bearer bar 26. Each furnace 13a, 13b is provided with grates 40 18 and an arch 27 consisting of refractory material 28 supported by the tubes 29. Rearward of the back wall 20 is a cab 30 having a deck 31 above which deck the back wall 20 is provided with a pair of openings 32, 33, one for each furnace 13a, 13b, respectively. Each opening 32, 33 is arranged to permit access to the interior of a respective furnace 13a, 13b in order to supply each with fuel and for maintenance purposes.

A stoker S supplies fuel into each furnace 13a, 13b in a manner hereinafter to be described. This stoker comprises a conveyor 34 leading forwardly from the fuel supply bin on the tender T, and a fuel conveyor 35 disposed on the locomotive arranged to receive fuel from

the conveyor 34 and deliver it into the firebox 12. The conveyor 34 includes a trough conduit 36 having a screw 37 therein arranged to urge fuel against a crusher 38 and deliver the crushed fuel in a chamber or hopper 39 which is disposed on the locomotive and forms a portion of the conveyor 35. At its forward end, the trough conduit 36 is provided with a ball member 40 fitted into a spherical seat 41 of the hopper 39 to form a universal connection 42 between the conveyors 34 and 35. Rollers 43 carried by the trough conduit 36 afford flexible support for the conveyor 34 on the tender T.

Immediately forward of the conveyor screw 37, 15 the hopper 39 is provided at a respective side thereof with a jet member 44, 45. The jet member 44 receives pressure fluid from a supply line 46 while the jet member 45 receives pressure fluid from a supply line 47. Each jet member 44, 45 is 20 arranged to issue blasts of pressure fluid forwardly through a respective curved tubular conduit 48, 49, the former communicating with the opening 32 of the primary furnace 13a while the latter is in communication with the opening 33 25 of the auxiliary furnace 13b.

Crushed fuel delivered to the hopper 39 passes into the zone of action of jet members 44, 45 for propulsion through the respective tubular conduits 48, 49. At the forward end of each tubular conduit 48, 49 in a distributor member 50, 51, respectively, for spreading fuel evenly over the grates 18 of the furnaces 13a, 13b. The portion of each firing opening 32, 33 below a distributor member 50, 51 is closed by a door 52, 53, 35 respectively, each of which is provided with a power operating mechanism 54. A divider 55 is provided in the hopper 39 and it may be manually adjusted at any suitable angle to control delivery of fuel to each jet member 44, 45. A 40 multicylinder engine 56 operates the conveyor screw 37 by means of shafting 57 and suitable gearing (not shown) which connects the screw 37 and the shafting 57 in known manner. A line 58 supplies pressure fluid for operating the engine 56.

When the locomotive L is operating the primary furnace 13a is supplied with fuel at a more or less constant rate, while the auxiliary furnace 13b receives fuel only at times when high 50 operating peaks are to be reached. These peaks may occur while the locomotive is negotiating steep grades or hauling a heavy train. Under these conditions it is essential that a high steam output of the locomotive boiler, at high pressures, be attained. Accordingly, means, responsive to 55 pressure of steam within the boiler, are provided for controlling the operation of the stoker S in a manner to achieve adequate delivery of fuel to both furnaces 13a, 13b when the pressure of steam within the locomotive boiler 12 reaches a predetermined minimum point. This means also functions to interrupt delivery of fuel to the auxiliary furnace 13b when the pressure of steam within the boiler 12 reaches a predetermined 60 maximum point.

Secured to the back wall 20 is a valve V comprising a casing 59 within which is mounted a piston valve 60. Steam is conducted to the valve casing 59 by a pipe 61 leading from the line 58. 70 On one side of the piston valve 60 is a spring 62, the tension of which may be adjusted by the hand nut 63 so that the piston valve 60 may be balanced in the position shown in Figure 5 against the pressure of steam on the right side of the valve 60 as supplied by a pipe 64 leading

from the boiler 12. It is to be understood that when the valve 60 is balanced in the position shown in Figure 5, the pressure of steam in the boiler 12 is being maintained at the required point by operation of the primary furnace 13a only.

The piston valve 60, when in the position shown in Figure 5, closes off the port 65 from which lead the pipes 47 and 66, the pipe 47 supplies pressure fluid (steam) to the jet member 45 while the pipe 66 supplies steam to a cylinder 67 which is mounted upon the transmission gear case 68. Within the gear case 68, which is secured to the engine 56, are the shafts 69 and 70; the former being journaled within the crank-shaft 71 of the engine and carrying a coupling 72 on its exterior portion to which coupling the shaft 57 is operatively connected. A gear 73 is made fast to the end of the crankshaft 71 and it meshes with a slightly larger gear 74 loosely mounted on the shaft 70; the latter shaft has keyed thereto a gear 75 which meshes with slightly larger gear 76 secured to the shaft 69. Gears 73 and 74 are provided with clutch teeth 73a, 74a arranged for selective engagement by clutches 77 and 78 slidably keyed upon shafts 69 and 70, respectively. The clutches 77, 78 are arranged to engage or disengage the clutch teeth 73a, 74a, by means of a shifter 79 secured to a shaft 80, for causing gears 73, 74, to rotate or to idle with reference to the shafts 69, 70, respectively.

The shaft 80 extends above the gear case 68 into a housing 81 and has secured thereto an arm 82 which has an operative connection with the rod 83 of piston 84. This piston 84 is disposed within the cylinder 67 which latter is secured to the housing 81. In the absence of pressure fluid reaction on piston 84, as supplied by pipe 66, a spring 85 maintains the piston 84, and consequently the clutch shifter 79 in the position shown in Figures 6 and 7, respectively.

Assuming that the locomotive L is operating under a light load, only the primary furnace 13a will be supplied with fuel, and the piston valve 60 will be balanced in the position shown in Figure 5. When steam consumption by the locomotive increases due to a heavier load, or for other reasons, the pressure of steam within the boiler 12 will be lowered. This causes a corresponding drop in pressure of steam reacting upon the right side of piston valve 60, whereupon the spring 62 will force the valve 60 to the right and establish communication between the pipe 61 and the port 65.

In this manner, steam is conducted to the jet member 45 by means of the pipe 47 so that the fuel within the hopper 39 will be propelled through the tubular conduit 49 over the grates 18 of the auxiliary furnace 13b. Simultaneously, steam will be admitted to the pipe 66 for moving the piston 84 against the tension of the spring 85. This will cause rotation of the shaft 80 whereby the shifter 79 will move clutch 78 to a disengaging position with reference to the clutch teeth 74a of gear 74, while clutch 77 engages the teeth 73a of gear 73. Thus the crankshaft 71 operates the shafting 57 directly in order that the conveyor screw 37 may deliver the greater quantities of fuel necessary to supply the primary and auxiliary furnaces. When only the primary furnace 13a is operating the clutch shifter 79 is in the position shown in Figure 6, whereby the shaft 69, and consequently shafting 57, is operated through the reduction gearing 73, 74, 75 and 76 so that the shaft 69 rotates at a speed about one-

half of that of the crankshaft 71. This is necessary in order that an oversupply of fuel may not be delivered into the hopper 39 when only the jet member 44 is operative.

5 Since there may be prolonged periods during which the auxiliary furnace 13b does not receive fuel, a pilot fire is maintained at all times in this furnace. For this purpose, unconsumed particles of fuel deposited within the smokebox 15 are caused to drop into a trough 90 from which they are propelled forwardly by jets of pressure fluid issuing from the head 91. The fuel particles are propelled forwardly through a tube 92 which communicates with the auxiliary furnace 13b. It will be understood that before the locomotive is placed on the out-going track, a fire is built up and maintained in each furnace 13a, 13b in the usual manner. However, when the stoker S is delivering fuel to the primary furnace 13a, the unconsumed products of combustion therein, which are sometimes considerable due to the type of fuel used, are delivered from the smokebox 15 into the auxiliary furnace 13b. This arrangement will efficiently 25 maintain a light fire within the auxiliary furnace 13b so that when the stoker S supplies fuel to the auxiliary furnace as hereinbefore set forth, a heavier fire may be quickly attained.

In the modification illustrated in Figure 8, 30 the locomotive L is of a construction similar to that shown in Figures 1 and 7, inclusive, and includes a boiler 112, the firebox 113 of which is divided into the primary furnace 113a and the auxiliary furnace 113b by means of a water 35 circulating wall 124. Each furnace 113a, 113b is provided with a respective firing opening 132, 133 in the back wall 120. The stoker S includes a fuel conveyor 135 disposed on the locomotive L above the frame 100 thereof and having a 40 hopper 139 into which fuel is delivered by a conveyor such as that indicated by 34 in Figures 1 and 2. Within the hopper 139 is a divider 155 operable to apportion the amounts of fuel delivered to the lower end of each elevating screw 95, 96 received in the tubular conduit 148, 149, respectively. The elevating screw 95 urges fuel upwardly along the conduit 148 and deposits the fuel in front of a jet member 144 which projects the fuel through a distributor 45 member 150 for distributing the fuel to all parts of the firebed in the primary furnace 113a. Likewise, the screw 96 delivers fuel into the zone of action of jet member 145 which projects the fuel through the distributor member 151 and 50 over the firebed in the auxiliary furnace 113b. Pressure fluid such as steam is conducted to the jet members 144, 145 by pipes 146, 147, respectively.

The hopper 139 is provided with a bore 97 55 which houses and serves to maintain in operative relation the gearing for operating the screws 95, 96 in a manner well known in the art, as in Patent No. 1,828,116, granted October 20, 1931. At one side of the hopper 139 is an engine 158 which operates a shaft 101 having mounted thereon the worm gears 102 and 103, operatively 60 associated with the screws 95, and 96, respectively. The worm gear 102 is made fast to shaft 101 while the worm gear 103 is loosely mounted thereon but arranged to be keyed to the shaft 101 through the intermediary of a clutch 104. Power is also supplied from the engine 158 for operating a shaft 157 which is arranged to drive, at proper rates of speed, a suitable conveyor screw (such as that shown at

37 in Figure 2) for delivery of fuel into the hopper 139.

A worm gear 105 is loosely mounted on the end of shaft 101 and it meshes a worm wheel 106 which is keyed to the shaft 157. The worm gear 105 may become keyed to the shaft 101 by means of a clutch 107 whereupon a direct drive is attained for the worm gear 105. In order to provide for a reduced speed of the worm gear 105, and consequently, a reduced speed for the shaft 157 and the conveyor screw connected thereto, the worm gear 105 has secured thereto a gear 108 meshing with a gear 109 on the countershaft 115 in the gear case 168. The countershaft 115 also carries a gear 116 in mesh with a gear 117 loosely mounted on the shaft 101. The clutch 107 is arranged to engage gear 117 for keying the same to shaft 101 whereupon the worm gear 105 will be operated through speed reduction gearing 117, 116, 109, 108. Movement of clutches 104 and 107 is accomplished through shifters 8 and 9 respectively, each of which are mounted on a rod 7.

As in the preferred embodiment of our invention, a valve V is utilized to control the operation of the stoker S as determined by steam requirements of the locomotive. The valve V receives steam through a pipe 161 which is connected to the main supply lead 158, the latter 25 supplying pressure fluid for operating the engine 30 156. Supply line 146 for the jet member 144 also is connected directly with the main lead 158. The pipe 147, which admits steam to the jet member 145 receives steam from the valve V as does the pipe 166 which conducts steam 35 to the cylinder 167 for operating the piston 184 against the tension of spring 185. One end of the clutch operating rod 7 is secured to the piston 184.

In the operation of this embodiment of our 40 invention, the parts are in the position shown in Figure 8 when the fire in the primary furnace 113a is sufficient to maintain the pressure of steam in the locomotive boiler at the required point. Upon any substantial reduction of steam 45 pressure in the boiler, the valve V acts to admit steam to pipes 147 and 166, which causes operation of the elevating screw 96 and jet member 145. It will also be apparent that more fuel will be delivered into the hopper 139 because 50 a direct drive for worm gear 105 has been attained. In this manner, fuel will be supplied to the auxiliary furnace 113b. A pilot fire within the auxiliary furnace 113b is maintained by the feeding of unconsumed particles of fuel resulting 55 from combustion within the primary furnace 113a.

From the foregoing, it will be apparent to those familiar with the art that a highly efficient stoker has been provided for feeding fuel to the several furnaces of a single boiler. While 60 the invention has been described in connection with a locomotive boiler it is to be understood that its use is not limited to this field alone and that features of our invention are of general application.

65 We claim:

1. In a fluid boiler having a firebox, a stoker for delivering fuel into the firebox comprising a pair of conveyors delivering to said firebox, a conveyor for supplying fuel to said first named conveyors, means for operating said last named conveyor including a change-speed transmission, a pressure fluid jet member associated with each of said pair of conveyors for projecting fuel into the firebox, pressure fluid means for operat-

- ing said change-speed transmission, and means responsive to pressure of fluid in said boiler for controlling the flow of pressure fluid to the second named means and to one of said jet members.
2. In a fluid boiler having a firebox, a stoker for delivering fuel into the firebox comprising a pair of conveyors delivering to said firebox, a conveyor for supplying fuel to said first named conveyors, means for operating said last named conveyor including a change-speed transmission, a pressure fluid jet member associated with each of said pair of conveyors for projecting fuel into the firebox, pressure fluid means for operating said change-speed transmission, and means responsive to a drop of pressure fluid in said boiler below a predetermined point for admitting pressure fluid to one of said jet members and to the second named means for operating said change-speed transmission.
3. In a fluid boiler having a firebox, a stoker for delivering fuel into the firebox comprising a pair of conveyors delivering to said firebox, gearing for operating said conveyors including a clutch arranged to engage or to disengage said gearing from operative relation with one of said conveyors, a conveyor for supplying fuel to said first named conveyors, change-speed transmission gearing for operating said last named conveyor including a clutch for controlling said change-speed transmission gearing, and means responsive to pressure of fluid in said boiler for operating said clutches.
4. In a fluid boiler having a firebox, a stoker for delivering fuel into the firebox comprising a pair of conveyors delivering to said firebox, gearing for operating said conveyors including a clutch arranged to engage or to disengage said gearing from operative relation with one of said conveyors, a conveyor for supplying fuel to said first named conveyors, change-speed transmission gearing for operating said last named conveyor including a clutch for controlling said change-speed transmission gearing, a pressure fluid jet associated with each of said pair of conveyors and arranged to receive fuel therefrom for projection into the firebox, and means responsive to pressure of fluid in said boiler for controlling the supply of fluid to one of said jet members and also for operating said clutches.
5. In a fluid boiler having a firebox, a stoker for delivering fuel into the firebox comprising a plurality of fuel feeding units, a conveyor, mechanism for rendering said conveyor operative to supply fuel to said fuel feeding units at desired rates of feed, means for rendering the fuel feeding units operative to deliver into the firebox the fuel received from said conveyor, means responsive to pressure of fluid in said boiler for interrupting operation of one of said fuel feeding units, and added means cooperating with the second named means for reducing the rate of delivery of said conveyor without substantial change in the rate of delivery of the other of said fuel feeding units.
6. In a fluid boiler having a firebox, a stoker for delivering fuel into said firebox comprising a plurality of fuel feeding units, a conveyor, mechanism for rendering said conveyor operative to supply fuel to said fuel feeding units at desired rates of feed, means for rendering the fuel feeding units operative to deliver into the firebox the fuel received from said conveyor, means responsive to increase in pressure of fluid in said boiler above a predetermined point for interrupting operation of one of said fuel feeding units, and added means cooperating with the second named means for reducing the rate of delivery of said conveyor without substantial change in the rate of delivery of the other of said fuel feeding units.
7. In a fluid boiler having a firebox, a stoker for delivering fuel into said firebox comprising a plurality of fuel feeding units communicating with said firebox, pressure fluid means for urging fuel through said fuel feeding units and into said firebox, a conveyor, mechanism for rendering said conveyor operative to supply fuel to said fuel feeding units at desired rates of feed, means responsive to pressure of fluid in said boiler for interrupting conveyance of fuel through one of said fuel feeding units by pressure fluid means, and added means cooperating with the second named means for reducing the rate of delivery of said conveyor without substantial change in the rate of delivery of the other of said fuel feeding units.
8. In a fluid boiler having a firebox, a stoker for delivering fuel into said firebox comprising a plurality of fuel feeding units communicating with said firebox, pressure fluid means for urging fuel through said fuel feeding units and into said firebox, a conveyor, mechanism for rendering said conveyor operative to supply fuel to said fuel feeding units at desired rates of feed, means responsive to increase in pressure of fluid in said boiler above a predetermined point for interrupting conveyance of fuel through one of said fuel feeding units by pressure fluid means, and added means cooperating with the second named means for reducing the rate of delivery of said conveyor without substantial change in the rate of delivery of the other of said fuel feeding units.
9. In a fluid boiler having a firebox, a stoker for delivering fuel into said firebox comprising a plurality of fuel feeding units, a conveyor for delivering fuel to said fuel feeding units, mechanism for rendering said conveyor operative at desired rates of speed, means for rendering the fuel feeding units operative to deliver into the firebox the fuel received from said conveyor, means responsive to pressure of fluid in said boiler for interrupting operation of one of said fuel feeding units, and added means cooperating with the second named means for reducing the speed of said conveyor without substantial change of speed of the other of said fuel feeding units.
10. In a fluid boiler having a firebox, a stoker for delivering fuel into said firebox comprising a plurality of fuel feeding units, a conveyor for delivering fuel to said fuel feeding units, mechanism for rendering said conveyor operative at desired rates of speed, means for rendering the fuel feeding units operative to deliver into the firebox the fuel received from said conveyor, means responsive to increase in pressure of fluid in said boiler above a predetermined point for interrupting operation of one of said fuel feeding units, and added means cooperating with the second named means for reducing the speed of said conveyor without substantial change of speed of the other of said fuel feeding units.
